(57) **CLAIM**

The ornamental design for a storage case for feeding bottle cleaning tools, as shown and described.

DESCRIPTION

FIG. 1 is an exploded view of a storage case for feeding bottle cleaning tools showing my new design;

FIG. 2 is a front elevational view thereof;

FIG. 3 is a rear elevational view thereof;

FIG. 4 is a left side view thereof;

FIG. 5 is a right side view thereof;

FIG. 6 is a perspective view thereof;

FIG. 7 is another perspective view thereof;

FIG. 8 is a perspective view of the top cover alone while other components are omitted for the purpose of clearer illustration; and,

FIG. 9 is another perspective view of the top cover alone while other components are omitted for the purpose of clearer illustration.

The broken lines in FIGS. 1-8 illustrate portions of the storage case for feeding bottle cleaning tools. The broken lines in FIG. 9 illustrating a strap and cleaning tools represent environment. None of the broken lines form part of the claimed design.
